(57) **CLAIM**

The ornamental design for a plant lamp head, as shown and described.

DESCRIPTION

FIG. 1 is a front perspective view showing a plant lamp head in accordance with one embodiment of the present invention;

FIG. 2 is a front elevation view of FIG. 1;

FIG. 3 is a rear elevation view of FIG. 1;

FIG. 4 is a right side view of FIG. 1;

FIG. 5 is a left side view of FIG. 1;

FIG. 6 is a top plan view of FIG. 1;

FIG. 7 is a bottom plan view of FIG. 1; and,

FIG. 8 is a rear perspective view of FIG. 1.

The broken-line disclosure represents the portion of the plant lamp which forms no part of the claimed design.
